DESIGN FOR A HOT DISH PAD OR SIMILAR ARTICLE

Thomas T. Grimsdale, New York, N. Y., assignor to Frank M. Sayford Co., Inc., Brooklyn, N. Y.

Application August 20, 1938, Serial No. 79,479

Term of patent 3½ years

To all whom it may concern:

Be it known that I, Thomas T. Grimsdale, a citizen of the United States, residing at New York city, in the county of New York and State of New York, have invented a new, original, and ornamental Design for a Hot Dish Pad or Similar Article, of which the following is a specification, reference being had to the accompanying drawing, forming a part thereof.

In the drawing:

The characteristic features of the design, which are shown in full lines, reside in the matched scenic representations in the upper corners thereof whereby the bridge on the one side and the sea wall on the other complete the general outlines of a curve; the setting off of the several scenes by the diagonal lines radiating from the central circular outline; and the outstretched wings of the eagle positioned centrally between the lower corner scenes, all as shown.

I claim:

The ornamental design for a hot dish pad or similar article, as shown and described.

THOMAS T. GRIMSDALE.
